DENTIFRICE CONTAINER AND DISPENSER

Arthur W. Beaumont, New York, N. Y., and
William A. Shenton, Montclair, N. J.

Application January 9, 1936, Serial No. 58,424

3 Claims. (Cl. 221—79)

The device of the present invention consists of a container for dentifrices, and like semi-solid substances having for an object the provision of a container which is noncollapsible and capable of being held in one hand of the user, and the contents dispensed by the same hand.

In the present invention, the container and dispensing mechanism for the contents of the latter is of simple construction, the dispensing mechanism being controlled by a terminal of the container which terminal is of a size conveniently fitting between the thumb and forefinger of the user to permit rotation while the body of the container is held stationary in the palm of the hand.

Of the essence of importance in the present invention is the construction of and manner of assembling the operating end of the container to insure positive operation of the extruding mechanism for dispensing the contents of the container in a predetermined volume, the rate of flow being also completely within the control of the user.

Other objects of the invention will be apparent from the following description of the present preferred forms of the invention taken in connection with the accompanying drawing, wherein:

Fig. 1 is a perspective view of a container constructed in accordance with the present invention, showing the closure cap removed from the dispensing end of the container.

Fig. 2 is a longitudinal sectional view of a container made in accordance with the present invention, showing the closure cap mounted thereon.

Fig. 3 is a sectional view taken on the line 3—3 of Fig. 2 showing to advantage the manner of mounting the follower piston on the shaft and in the container.

Fig. 4 is a detail fragmentary longitudinal sectional view of a modified form of container and follower, wherein the follower is provided with a peripheral lug extending into a complementary groove in the container wall, and showing also a modified form of nozzle.

Fig. 5 is a detail fragmentary longitudinal sectional view of still another modified form of container and follower in which a different mode of assembling the shaft head and nozzle is illustrated.

Fig. 6 is a cross sectional view of another modified form which includes an oval shape container with a complementary formed follower.

Fig. 7 is an end elevational view of the con-

tainer, looking at the closed end, showing the contour of the periphery, and

Fig. 8 is a detail fragmentary sectional view of still another form of the invention showing a further mode of assembling the shaft head and nozzle wherein the head is completely embedded in the nozzle.

The device of the present invention consists of a container 8 which may be of cylindrical configuration, as shown in Figs. 1 to 5 of the drawing, or ovoidal, as illustrated in Fig. 6. One end of the container is closed and provided with air vents, the opposite end being open and having mounted therein a nozzle, generally designated 10. The container may be made of paste-board, or any suitable material not adapted to be collapsed during use thereof.

The inner end of the nozzle is reduced in diameter and has a locking bead 11 formed on the outer periphery of said reduced portion which is adapted for engagement in a complementary recess formed in the inner wall of the container body. By reducing the diameter of the inner end of the nozzle, a shoulder is provided which abuts the outer free end of the container body, as illustrated to advantage in Fig. 2. When the nozzle is urged into the container body, the latter will yield sufficiently to permit the bead 11 to snap into the annular recess of the container body thereby locking the nozzle. The outer wall of the nozzle issues into a dispensing terminus 12 which in the present instance is shown to be of truncated cone shape and in which an opening 13 is formed. The contents of the container body may be dispensed through the opening 13 of the nozzle in a manner which will hereinafter appear. There is sufficient play between the nozzle and container body to permit the nozzle to be freely rotated and to assist this operation, we have formed grooves 14 in the outer wall of the nozzle.

For dispensing the contents of the container body, we provide dispensing mechanism which in the present instance consists of a screw threaded shaft 15, one end 16 of which is journaled in the closed end of the container body, the opposite end of the shaft being equipped with a head 17 which may be of rectangular cross section, the head being mounted in recesses 18 which are formed in the inner end of the nozzle 10. The screw shaft carries a follower 19 which may be of discal formation, as shown to advantage in Fig. 2, the follower being fed along the shaft 15 by rotation of the nozzle 10.

When not in use the dispensing end of the container body is closed by a cap 20, the latter being

provided with a recess 21 in which the outer end of the dispensing terminus 12 is seated. The cap 20 may be frictionally engaged with the outer periphery of the container body 8, as shown 5 in Fig. 2.

In the form of invention shown in Figs. 1 and 2, the container body is of cylindrical configuration and we prefer to provide suitable means to prevent the container from rolling when placed 10 on a support. For this purpose, we have in Figs. 1 and 7 shown the periphery of the container body, at the closed end of the latter, to be polygonal, as indicated at 21.

In the form of invention shown in Fig. 3, we 15 prefer to retain the follower 19 from rotative movement by forming a rib 22 on the inner periphery of the container body which extends longitudinally of the latter and engages a corresponding recess in said follower. However, in 20 the form of invention shown in Fig. 4 of the drawing, we provide a longitudinally extending groove 23 in the inner wall of the container in which a peripheral lug 24, formed on the follower 19, is mounted. Additionally in the form 25 of invention shown in Fig. 4, we prefer to make the nozzle in two parts consisting of inner and outer members 25 and 26, respectively, the latter having the head 17' of the screw shaft 15' embedded therein. The inner part 25 of the nozzle 30 has one end bent at right angles to engage beneath a circular extension 27 formed on the outer end of the container body. Said circular extension may be provided on its outer face with protrusions 28 which engage the inner wall of the 35 outer part 26 of the nozzle to reduce frictional resistance when the nozzle is rotated for actuating the shaft and its follower. As shown in Fig. 4, an opening is provided through the nozzle in this form of invention permitting the contents 40 of the container to be dispensed therethrough as the follower 19 is moved toward the nozzle end of the container.

In Fig. 6 of the drawing, we have shown a 45 container 8' which is of ovoidal configuration having movably mounted therein a follower piston 19' of complementary construction. The piston is movably mounted on a screw threaded shaft 15' operated in the same manner as the shaft 15 shown in Fig. 2. In this form of invention, 50 it is unnecessary to key the piston to the container since rotation of the piston is prevented by the inherent construction of the piston and container.

In Fig. 5, we have shown another preferred 55 form of assembling the shaft head, nozzle and container. In this form of the invention, the container 8 has a portion of its outer end extended to provide a collar 25, the diameter of which is smaller than the diameter of the container. 60 The collar is provided with an annular groove 26, which is adapted for the reception of a complementary bead or ring 27, which latter is formed on the inner wall of a combination operating collar and nozzle 28. The combination cap and 65 nozzle includes a pair of parallel lugs 29 which extend inwardly from the outer end of the nozzle. Each of said lugs is bifurcated, as indicated at 30, to provide recesses in which the head 31 of the shaft 14 is seated. The combination collar and nozzle is provided with a suitable outlet terminal, such as shown at 12 in Fig. 2, through 70 which the contents of the container is extruded when the follower is operated. The combination collar and nozzle are preferably made of yieldable material to permit the collar to be flexed

over the bead 27. This construction permits the collar to be rotated to correspondingly rotate the head 30 of the follower shaft. Furthermore, this construction prevents displacement of the collar from the container. The collar and container 5 are of the same external diameter.

In the form of invention shown in Fig. 8, the nozzle is formed in one piece, the inner end 32 thereof fitting beneath a flange 33 formed by extending a portion of the free end of the container body inwardly. The dispensing terminus 34 of the nozzle projects outwardly beyond the flange 33 and has an operating collar 35 fixedly mounted thereon. In this form of invention, the head of the operating screw shaft is completely 15 embedded in the inner end 32 of the nozzle. The nozzle is rotated by operation of the collar 35 in a manifest manner so as to actuate the screw shaft. A closure cap 36 may be mounted over the collar 35 in snug engagement with the dispensing terminus 34 of the nozzle to seal the opening in the terminus.

In use of this device, when the piston follower is in the bottom of the container body, as shown in Fig. 1, and before the nozzle has been inserted, the dentifrice or other material to be dispensed is deposited in the container body on top of the follower. After the container is filled, the nozzle is snapped into position which locks it from displacement although a rotative movement 30 is permitted. This rotative movement may be accomplished by the thumb and a finger of the hand in which the container is carried, the operating portions of the container being rounded to facilitate gripping of these parts by the fingers. 35 It is apparent that the nozzle may be rotated in either direction so that after the desired quantity of dentifrice or other material has been dispensed, by movement of the nozzle in one direction, a slight movement in the opposite direction 40 prevents casual displacement of the container contents.

While we have herein shown pistons and container bodies of cylindrical and oval configuration, it is nevertheless within the contemplation 45 of this invention to use containers and pistons of other contours.

While we have herein shown and described preferred forms of my invention, it is nevertheless to be understood that various changes may 50 be made in the details of construction, proportion and arrangement of parts within the scope of the claims herewith appended.

What is claimed is:

1. A plastic material container and dispenser 55 comprising a hollow body closed at one end and open at the other end, the closed end of the body having an air vent, a nozzle engaging the open end of the body and having a portion thereof projecting interiorly of the body, said body 60 having a groove on the inside inwardly of the open end, a bead on the inwardly projecting portion of the nozzle engaging in said groove, a threaded shaft disposed axially of the body, a follower threadedly engaging said shaft and slidably engaging the container, said nozzle having opposed notches in the inner end thereof, and a bar secured to the adjacent end of the shaft and engaging in said notches to hold the shaft against rotation relative to said shaft. 70

2. A plastic material container and dispenser comprising a hollow body closed at one end and open at the other end, the closed end of the body having an air vent, a nozzle engaging the open end of the body and having a portion thereof 75

projecting interiorly of the body, said body having a groove on the inside inwardly of the open end, a bead on the inwardly projecting portion of the nozzle engaging in said groove, a threaded 5 shaft disposed axially of the body, a follower threadedly engaging said shaft and slidably engaging the container, said nozzle having opposed notches in the inner end thereof, a bar secured to the adjacent end of the shaft and engaging 10 said notches to hold the shaft against rotation relative to said shaft, and a cap enclosing said nozzle and engaging the adjacent end of the container.

3. A plastic material container and dispenser 15 comprising a hollow body closed at one end and open at the other end, the closed end of the body having an air vent, a nozzle engaging the

open end of the body and having a portion thereof projecting interiorly of the body, said body having a groove on the inside inwardly of the open end, a bead on the inwardly projecting portion of the nozzle engaging in said groove, a threaded 5 shaft disposed axially of the body, a follower threadedly engaging said shaft and slidably engaging the container, means for holding the follower against rotation while permitting slideable movement thereof in the container, said nozzle having opposed notches in the inner end thereof, and a bar secured to the adjacent end of the shaft and engaging in said notches to hold the shaft against rotation relative to said shaft. 10
